UNITED STATES PATENT OFFICE.

VICTOR GUINZBURG, OF NEW YORK, N. Y., ASSIGNOR TO I. B. KLEINERT RUBBER COMPANY, A CORPORATION OF NEW YORK.

SANITARY GARMENT-PROTECTOR.

1,093,616,

Specification of Letters Patent. Patented Apr. 21, 1914.

Application filed July 20, 1911. Serial No. 639,609.

To all whom it may concern:

Be it known that I, VICTOR GUINZBURG, a citizen of the United States, and a resident of the borough of Manhattan, city, county, and State of New York, have invented certain new and useful Improvements in Sanitary Garment-Protectors, of which the following is a specification, accompanied by drawings.

10 The invention relates to protectors for use beneath women's skirts and adapted to be secured around the waist of the wearer hanging down in the rear below the knees of the wearer, the upper portion in the vicinity of the hips being of thin and pervious material and the lower portion impervious.

In order to fit the person of the wearer without wrinkling, various provisions have been made, such, for example, as shown in 20 Aiken patent of September 22nd, 1908, 899,196, wherein the upper portion having tapered plaits or folds on each side of the median line is secured to and supports an impermeable portion comprising a single 25 ply of material dependent from the yoke portion.

The present invention seeks to provide a protector which shall obviate the need of gores, plaits or folds and the need of a separate upper and lower portion, and consists in its most preferred form of the following:

As shown in the accompanying drawings, Figure 1 is a rear view of the protector in 35 position, tied around the person of the wearer, and Fig. 2, the protector removed.

The improved protector comprises a waist band or tape B for securing it around the waist; also preferably a safety pin C which 40 is passed through two eyelets just below the waist band in the median line in the rear; and the protector proper which consists of a single sheet of fabric, the upper part of which is of loosely woven, preferably cotton, 45 fabric, adapted to yield, stretch and conform substantially without wrinkles to the waist and hips, while the lower portion D of the same fabric is rubbered or made impervious by filling its interstices and preferably covering the whole surface of this portion of the fabric with a suitable waterproof material, of which a rubber compound 50 is the best example.

The loose, openwork, unrubbered portion F stretches very readily to the degree neces-

sary to conform to the curvature of the person without requiring to be specially fitted and without requiring any seam between it and the portion D; while, on the other hand, the portion D, while very flexible, is sufficiently stiff to facilitate its remaining in proper position hanging down without undue wrinkling.

It will thus be seen that in this new protector the upper and lower portions are of different character seamlessly united and cooperating in a novel manner to make the article peculiarly neat and comfortable, while effectively serving its protective function. The lower relatively stiff portion is necessarily slightly weighted by the addition of the rubber or other compound by which it is made impervious and is well adapted to hang smoothly and evenly when properly supported at its seamless junction with the upper portion. The upper portion being relatively thin, light, pervious and stretching fabric, is not only adapted to yield and stretch in conforming to the back of the figure between the waist tape or band and the stiffer lower portion, but, in addition, it directly cooperates to afford to the lower hanging portion a relatively stretching and accommodating support, thus facilitating the relatively stiff portion hanging more evenly from it than if the upper portion were equally stiff. Also, it will be seen that the lower impervious portion, in addition to its protective and well-hanging qualities, cooperates to afford to the more stretching portion a relatively stiff but seamless lower boundary, and it will be seen that there is no transverse ridge or seam to break the smooth curve of the fabric where the impervious portion D joins the thin yielding portion F or to irritate the flesh particularly if worn under corsets or confining outer garments, and the need of plaits, folds or seams to enable the upper portion to fit the person is done away with, and such upper portion is free from the stiffness and the heating or plaster-like qualities of impervious sheet material, even though the latter be perforated to lessen its discomfort.

Preferably the upper edge of the portion F when seen in a flat position, as in Fig. 2, is curved, concave upward, and the whole protector, F and D, widens downward to or near to the lower margin, which is also preferably curved, convex downward.

110

What I claim and desire to secure by these Letters Patent is:

1. A garment protector of the class described, comprising a waist tape or band and an integral sheet of textile fabric dependent therefrom consisting of lower and upper portions in seamless continuity, the lower portion having added to it a substance rendering it substantially impervious and also relatively stiffer, and being thereby adapted to hang smoothly and evenly from its seamless junction with the upper portion, the said upper portion being of relatively thin, light, pervious and stretching material adapted to readily yield and stretch to conform to the back of the figure in the area between the waist tape or band and such seamless junction, such upper stretching portion thereby also co-operating to afford to the stiffer hanging portion a more stretching and accommodating support, facilitating the latter hanging more evenly from the seamless junction with smooth and unbroken curves at such junction.
2. A garment protector of the type described, comprising an integral sheet of fabric consisting of two portions, the lower impervious and the upper pervious, the lower relatively stiff and the upper of relatively open and stretchable fabric, and a waist tape or band for securing the upper edge of the said upper portion, and means located below the waist tape or band for directly securing said upper portion against lateral displace-

ment, the said upper open and stretchable portion being adapted to conform by stretching without other fitting device to the person between the waistband and the relatively stiff lower portion.

3. A garment protector of the class described, comprising an integral sheet of foundation fabric of loosely woven, readily stretching and flexibly yielding character increasing in width from its upper edge downward to the lower edge, a securing waist-tape or band secured along and continuous with the upper edge of said flexibly yielding fabric and having free ends extending outward therefrom, and a layer of impervious and stiffening material adherently united to and relatively stiffening the lower portion of said sheet, such portion embracing the greater lateral and longitudinal extent of said sheet, its upper edge seamlessly joining the relatively more yielding portion at a line sufficiently removed from the said tape or band to permit the upper and yielding portion to conform without wrinkling to the figure of the wearer and the impervious section to curve unbrokenly and drop pendently therefrom.

In testimony whereof I have signed this specification in the presence of two subscribing witnesses.

VICTOR GUINZBURG.
